Des. 211,965
Patented Aug. 13, 1968

211,965

COMBINED RADIO, PHONOGRAPH AND TELEVISION CABINET OR SIMILAR ARTICLE

John C. Kopf, New York, N.Y., assignor to Andrea
Radio Corporation, Long Island City, N.Y., a cor-
poration of New York

Filed June 5, 1967, Ser. No. 7,362

Term of patent 14 years

(Cl. D56—4)

FIG. 1

FIG. 2

FIG. 3

FIG. 4

FIG. 1 is a perspective view of a combined radio, phonograph and television cabinet or similar article showing my new design;

FIG. 2 is another perspective view thereof taken from a position substantially 120° counter-clockwise from that of FIG. 1;

FIG. 3 is another perspective view thereof taken from a position substantially 120° clockwise from that of FIG. 1; and

FIG. 4 is a top plan view thereof.

I claim:

The ornamental design for a combined radio, phonograph and television cabinet or similar article, as shown and described.
